(57) **CLAIM**

The ornamental design for a tire as shown and described.

DESCRIPTION

FIG. 1 is a side perspective view of a tire showing my new design, it being understood that the tread pattern is repeated throughout the circumference of the tire;

FIG. 2 is a front elevational view thereof; it being understood that the tread pattern is repeated throughout the circumference of the tire;

FIG. 3 is a side elevational view of the left side thereof; FIG. 4 is a side elevational view of the right side thereof; and,

FIG. 5 is an enlarged fragmentary front elevational view thereof taken along line 5-5 of FIG. 2;

In the drawings, the broken lines depict environmental subject matter only and form no part of the claimed design.
